UNITED STATES PATENT OFFICE.

ROBERT C. McCONACY, OF SOUTH YARRA, VICTORIA, AUSTRALIA.

APPARATUS FOR FORMING HINGED SHEET-METAL RECEPTACLES.

1,149,201.

Specification of Letters Patent. Patented Aug. 10, 1915.

Application filed November 19, 1912. Serial No. 732,210.

To all whom it may concern:

Be it known that I, ROBERT CHARLES McCONACY, a subject of the King of Great Britain, residing at Toorak Road, South 5 Yarra, in the State of Victoria, Commonwealth of Australia, manufacturer, have invented certain new and useful Apparatus for Forming Hinged Sheet-Metal Receptacles, of which the following is a specification.

This invention relates to apparatus to form receptacles and lids or covers with hinge members and to hingedly connect the receptacles and lids.

10 In the manufacture of covered receptacles of metal it is the custom in hingedly connecting the lids or covers to the receptacles to provide the receptacle and lid with folded portions and then connecting them by a wire engaging in such folded portions, the insertion of the wire ordinarily being a hand operation.

15 It is the principal object of the present invention to provide an apparatus to hingedly connect a lid to a receptacle, and to overcome the above disadvantage of having to insert a wire into bent or folded portions of the lid and receptacle to hingedly connect the two.

20 In carrying out the invention I provide an apparatus to "work up" hinge members wholly out of the material of the lid and receptacle by forming the lid or receptacle with integral hinge pintles and forming the 25 other with bulbed portions in which the pintles engage and then pressing the bulbed portions around the pintles or hinge pins.

30 In order that the invention may be readily understood, reference will now be had to the accompanying sheets of explanatory drawings, wherein:

35 Figures 1 to 6 are views in perspective of a small sheet metal receptacle and a lid showing the various stages through which they pass to hingedly connect one with the other according to the present invention. Figs. 7 to 10 are similar views showing a slight modification in the formation of the hinge. Fig. 11 is a view in front elevation 40 of the apparatus designed specially to perform the various operations necessary to automatically shape and hingedly connect the lids and the receptacles shown in Figs. 1 to 15. Fig. 12 is a view in side elevation of the 45 apparatus shown in Fig. 11. Figs. 13 to 23 are views of details in the construction of

the apparatus or machine and are herein-after fully described.

In these drawings like characters of reference have been employed to indicate similar parts in the different views and the numeral 1 designates the lid of the receptacle. The back of the lid, as shown by the prepared blank illustrated in Fig. 1 of the drawings, is made of greater depth than the ends thereof and is shaped somewhat in the form of an inverted letter T. The lugs or laterally projecting parts 4 of the T-shaped portion of the lid 1 and the metal lying therebetween is pressed or folded by means of dies or the like into the circular or semi-circular shape shown in Fig. 3 to form pintles or hinge-pins 3 upon which the lid may easily pivot when fitted in approved bearings formed on the receptacle. The bearings for the pintles 75 or hinge-pins 3 are formed on the back of the receptacle 2 by forming bulbs 5 thereon, as shown in Fig. 4. These bulbs 5 are the same distance apart as the pintles or hinge-pins 3 and are formed by dies or other approved means.

In forming the bulbs 5 the metal is stretched from the points marked 6—see Fig. 4—and at the same time vertical incisions 7 are made in the back of the receptacle at the inner ends of the bulbs. Moreover, the dies employed to make the bulbs 5 can be shaped to form a horizontal recess or depression 8 between the said bulb, as shown, and this recess is intended to permit 9 of the lid being operated freely when fitted to the receptacle. In an after operation an incision is made along the top and down the outer ends of the bulbs 5 to permit of the metal forming the latter being raised or pressed outwardly in the form of tongues sufficiently far to enable the pintles or hinge-pins 3 to be passed therebeneath. When the lid 1 and receptacle 2 are brought together 100 in this way the bulb portions are pressed back to their original positions and fit neatly around the pintles or hinge-pins 3 thus hingedly connecting the two parts in an extremely efficient manner.

105 In the modification illustrated in Figs. 7 to 10 of the drawings a T-shaped recess 8^a is cut in the back of the lid 1 to form inwardly projecting lugs 9 near the ends thereof—see Fig. 7. These lugs 9 are bent or folded into semi-circular or circular form, 110 as shown in Fig. 9, to make pintles 10 which are adapted to be passed beneath the raised

bulbs 11 formed on the back of the receptacle 2 and oppositely to those previously described. The bulb portions are pressed neatly around the pintles 10 to securely fasten the lid 1 to the receptacle 2 in the manner hereinbefore described. A hinge constructed as described will be strong, free in operation and will be very economical to manufacture.

10 I wish it particularly to be understood that although the process of bulbing prior to pressing out portion of the back of the receptacle is preferable it is by no means essential to the successful performance of the 15 invention as a strong and serviceable hinge could be formed simply by pressing part of the body outwardly and folding it around the pintles or hinge-pins on the lid.

The advantage obtained by first bulbing 20 the back of the receptacle is that when the metal is pressed back to its original position it will neatly surround the hinge-pins 3 and the edges formed by the incisions will be brought into contiguity and not be at 25 some distance apart as would otherwise be the case.

It will be obvious from the foregoing description that the salient feature in the construction of the hinge is the formation of 30 the pintles or hinge-pin integrally with the lid substantially as hereinbefore described.

It will be readily apparent to those skilled in the art to which the invention relates that the form of hinge herein described can 35 be readily employed to connect lids to receptacles of various shapes other than the rectangular type shown and which has simply been adopted to facilitate a clear understanding of the invention.

40 The apparatus devised to automatically shape and connect the hinged parts of the receptacles and lids is made in the form of a sheet metal press and consists essentially of a frame 12 of approved construction 45 which may be supported on a suitable stand or base. The upper end of the frame 12 is provided with a revolvably mounted driving shaft 13 having a combined belt and fly wheel 14 fitted to its rear end and an eccentric 15 adjustably mounted on its front end. The motion of eccentric 15 is adapted to impart a vertical reciprocatory motion to a ram 16 designed to move in guides 17 on the front of the frame. The lower end 50 of the ram 16 is provided with a head 16^a having suitably located bosses 18 or the like adapted to move freely over guide pillars 19 of approved construction fitted to a table 20. These bosses 18 and guide pillars 19 55 insure the ram head moving correctly up and down and like the parts before described are common in various kinds of sheet metal presses at present in use. Fitted to the underside of the ram head 16^a are 60 three top dies 21, 22 and 23 which are 65

adapted to move to and from a similar number of bottom dies 21^a, 22^a and 23^a, respectively, fitted in an approved way to the table 20. Any well known means can be employed to secure the dies in or effect an 70 adjustment of their position. The receptacles are passed along and treated on one side of the dies while the lids are passed along and treated on the opposite side of the said dies.

75 In the machine shown in the drawings the receptacles are passed along the front of the dies but this can be altered if preferred and the lids may be treated on the fronts and the receptacles on the backs of 80 the dies. The receptacles and lids are preferably fed to the right hand side of the machine through inclined chutes 24—shown in dotted lines—and are moved intermittently along horizontal plates 25 and 25^a 85 successively to each of the dies for forming the hinges and are discharged from the left hand side of the machine with the hinged lid properly fitted and neatly closed. The means devised for intermittently moving 90 the receptacles and lids from one set of dies to the other and discharging them from the machine comprises two endless conveyer chains 26 mounted on sprockets 27 fitted to spindles 28 supported revolvably in brackets 95 29 affixed to the frame. The said chains are fitted with fingers 26^a at regular distances apart which are adapted to bear against and push the receptacles and lids along the plates 25 and 25^a. The central 100 portion of the driving shaft 13 is fitted with a worm wheel (not shown) which meshes with a similar wheel 30 fitted to the upper end of a shaft 31 revolvably mounted in bearings fitted to the right hand side of the 105 frame 12. The lower end of the shaft 31 is fitted with a bevel wheel 32 which meshes with a similar wheel 33 on the outer end of a shaft 34 which passes transversely through and is revolvably mounted in the 110 frame 12 below the table 20. The opposite end of the shaft 34 is connected to the adjacent spindle 28 by means of Geneva bevel wheels 35 or other intermittently operating 115 gear. The intermittent gear operating the conveyer chains is constructed to positively lock the chains during the idle part of its rotation in any approved and well known way. The intermittent gear at each movement rotates the sprockets 27 sufficiently to 120 cause a receptacle disengaged from one die to be carried on to the next. The timing of the intermittent gear and that of the ram 16 is such that when the latter is near the end of its downward stroke and after 125 it has been raised some distance on its return stroke the former is stationary.

The receptacles and lids are forced from the plates 25 and 25^a on to the dies 21^a and 22^a by means of bell-crank levers 36 and

37 operating on push rods 38 and 38^a respectively having their inner ends fitted with enlarged flat heads or pressure pads 39. The bell-crank 36 is pivotally mounted in 5 a bracket 40 fitted to the front of the frame while the bell-crank 37 is similarly mounted in a bearing 41 located near the rear of the frame—see Fig. 14 of the drawings. The lower and inwardly projecting ends of 10 the bell-cranks 36 and 37 are formed with jaws 42 which are adapted to engage a short bar 43 arranged to be raised and lowered by the movement of a rocking lever 44 operated from a face cam 45 carried on 15 the continuously revolving shaft 34. The said rocking lever 44 is pivotally supported in a bearing 46 and its upper end is provided with a pin 47 adapted to fit the groove in the face cam 45. The lower end of the 20 rocking lever 44 is formed with a jaw 48 which is adapted to engage the bar 43 and when the lever is operated to raise and lower it to actuate the bell-cranks 36 and 37 and push rods 38 and 38^a. The upper 25 end of the bell-crank 37 is bifurcated to engage a bar 49 which connects up bosses 50 movably mounted on the push rods 38. The push rods 38^a are slidably mounted in 30 brackets 51 fitted to the table in an approved way and immediately behind each of the bottom dies. The bosses 50 and helical springs 52 are retained in a desired position on the push rods 38^a by adjustably fixed collars 53 or the like. The upper end 35 of the bell-crank 36 is also bifurcated and engages a bar 54 connecting bosses 50 on the two first push rods 38 in a like manner to that before described. The push rods 38 on the front of the machine are mounted 40 in brackets 51 similar to those located behind the dies 21^a, 22^a and 23^a. The object of the springs 52 is to provide a resilient buffer bearing for the bosses 50 operated by the movement of the bell-cranks 36 and 45 37 thereby obviating the exactness of adjustment that would otherwise be necessary, especially when the various parts become worn.

The push rod 38 designed to force the 50 receptacles on to the die 23^a has a greater movement than any other and is operated by a bell-crank 55 which is pivotally mounted in a bracket 56 affixed to the front of the frame 12. This said bell-crank 55 has a 55 short arm projecting forwardly from the pivot point and its extremity forms a pivotal connection with a rocking lever 57 supported in bearings 58 affixed to the frame. The rear or inner end of the rocking lever 60 57 is arranged to engage and receive its motion from the bar 43.

The push rods 38 and 38^a operate simultaneously and are timed to force the receptacles and lids upon the dies immediately the conveyer chains 26 cease moving.

ing and before the descent of the ram and top dies. When the ram and top dies are on their return or up stroke the receptacles and lids are removed from the bottom dies 21^a and 22^a by the outward movement of 70 the ejector rods 59 governed by leaf cams 60. The said ejector rods 59 are preferably recessed into the die blocks and are formed with flat circular heads or pads 61—see Figs. 19 and 20 of the drawings. The inner 75 ends of the ejector rods 59 are formed with laterally projecting pins or studs 62 which are adapted to fit snugly within inclined slots 63 formed in the leaf cams. The ejector rods 59 are arranged to be moved 80 outwardly and inwardly according as the leaf cams 60 are raised and lowered. In order to raise and lower the said leaf cams 60 rods 64 are arranged to depend therefrom and are adjustably fitted by means of 85 set screws 65 or the like to a horizontal bar 66. This bar 66 is raised and lowered at predetermined intervals by means of a rocking lever 67 which receives its motion from a face cam 68 fitted to the transverse 90 shaft 34.

It will be seen on referring to Fig. 20 that each leaf cam operates two ejector rods (one for the receptacles and one for the lids) in each die block 21^a and 22^a. 95

The receptacle and lid are hingedly connected to each other on the die 23^a and the ejector must travel a greater distance in this instance to return the receptacle to the sphere of influence of the conveyer chains. 100 To effect this desired amount of movement a small bell-crank 69 is employed having its lower and shorter end pivotally connected to a vertical rod 70 adjustably fitted to the bar 66. The upper and longer arm 105 of the bell-crank 69 is bent or disposed so as not to obstruct the receptacle while being forced on to the die 23^a and its extremity is provided with a pivotally attached bearing plate or pad 71 which is preferably recessed into the face of the said die. The enlarged heads or pads 39 on the ends of the push rods 38 and 38^a can be faced with leather, rubber or similar material to prevent injury to the surface of the lid or receptacle or to the enamel or lacquer covering the same. The said heads or pressure pads on the push rods are sufficiently large to serve as guide walls for the receptacles and lids passing from one set of dies to the next while plates 20^a can be located between the dies to prevent the said receptacles and lids being jammed and to insure them moving freely in a correct line. 110

The bottom dies overhang at the front 115 and back to give freedom for the fronts of the receptacles and lids when being pushed thereon and the leaf cams 60 operating the ejector rods reciprocate in vertical recesses formed therein. 120

The center die 22^a is provided near its front edge with one or more spring actuated compressible members 72 which are adapted to raise the receptacle from the projecting parts of the die, thereby permitting of the ready removal of the said receptacle. These compressible members are preferably inclined on their front faces, as shown in Fig. 22, and are normally kept in their raised position by springs 73. If preferred, compressible members similar to those above described can be fitted to each of the dies 21^a, 22^a and 23^a to raise the receptacles and lids from the shaping members of the die projecting above the tops thereof.

In operation, the machine is belt driven from any suitable source of power and the receptacles and lids are fed into the chutes 24, shown in dotted lines in Fig. 1, and 20 gravitate to the ends of the plates 25 and 25^a and within the sphere of operation of fingers 26^a formed on the conveyer chains 26. The said receptacles and lids are carried onward intermittently by the successive operations of the chains 26 until they are opposite the die 21^a. Immediately the chains become stationary the push rods 38 and 38^a are actuated to force the adjacent receptacle and lid upon the opposite sides of the said die. 25 The pressure of the push rods is maintained during the descent and the first part of the upward travel of the top dies and simultaneously with their release the ejector rods 59 are forced outwardly and return the receptacle and lid to the plates 25 and 25^a. The ejector rods 59 are returned to their original positions before the conveyer chains 26 move to carry the receptacle and lid to the second die 22^a. The first die 21^a forms 30 bulbs 5 on the receptacle, as shown in Fig. 4, while the depending portion of the back of the lid is given the shape shown in Fig. 3 of the drawings. If preferred, the formation of the pintles or hinge-pins 3 can be 35 formed partially on the back of the first die 21^a and completed on the second die 22^a. In this latter case both sides of the dies 21^a and 22^a will be brought into operation at each stroke of the ram, whereas in the 40 former case only the front half of the die 22^a will be used. When the receptacles 2 and lids 1 are brought directly in front of the second die 22^a the chains 26 are stopped and the said receptacle and lid are forced 45 on to the said die by the push rods 38 and 38^a in the manner before described. The die 22^a is shaped to form the incisions around the top and ends of the bulbs and raise the metal constituting the same, as 50 shown in Fig. 5. The next movement of the conveyer chains 26 carries the receptacle and lid directly opposite the third and narrow die 23^a upon which they are thrust by the third set of push rods 38 and 38^a. This 55 third die 23^a inclines upwardly on its rear

side and its front portion is cut away leaving the top equal or approximately equal in width to the depth of the receptacle. The plate 25^a along which the lids are moved is raised at the back of the die 23^a level with 70 a step 75 formed therein. When the receptacle and lid are forced upon the third die 23^a the pintles or hinge-pins 3 are passed beneath the raised bulbs and then these latter are pressed neatly around the 75 said pintles or hinge-pins by the pressure of the top die 23. Directly the top dies commence their upward stroke the push rods 38 and 38^a move outwardly as before described and simultaneously the small bell-crank 69 forces the receptacle back on to the plate 25, the lid passing over the top of the die 23^a. The further movement of the conveyer chains 26 carries the receptacle to a tapered chute 76 (shown in dotted lines 80 and in detail in Fig. 21 of the drawings) along which it is directed by the successive movements of the fingers 26^a until the lid is closed on the receptacle. The receptacles are directed by the chute 76 to any point 90 desired. The chute can be given any preferred construction and not necessarily that shown in the drawings.

It will be readily understood as the three sets of dies operate simultaneously and the 95 receptacles and lids are fed continuously to the machine that after the first two strokes of the ram a lid is hinged perfectly to a receptacle at each succeeding stroke thereof.

The apparatus may be modified in a variety of ways without departing materially from the construction herein described and it will be found particularly adaptable for securing the lids to tins in which tobacco, 105 confectionery, medicinal and chemical preparations and other goods are commonly packed.

What I do claim is:—

1. An apparatus for automatically hinging lids to receptacles made of sheet metal comprising a frame having a revolvably mounted driving shaft, a combined belt and fly wheel and an eccentric on said shaft, a ram reciprocatingly mounted in guides and operated from said eccentric, dies fitted to a head secured to said ram and located above a similar number of dies fitted to a table, endless conveyers located in front and behind the bottom dies and operated intermittently from gearing connected to the driving shaft, guides for the receptacles and lids in the front and rear of the bottom dies, means for pushing the receptacles and lids from the guides on to the dies and for returning them to said guides after being operated on by the dies, substantially as described.

2. In an apparatus or machine of the class described, the combination of a series 100

of sets of hinge-forming dies, the top die of each set being mounted on a reciprocatingly mounted ram and the bottom die of each set fitted to a table beneath, hinge-forming members on the faces of said dies, means for delivering lids and receptacles to guides in the front and rear of the bottom dies, endless conveyers for moving said lids and receptacles intermittently from one set of dies to another and for discharging the receptacles from the machine, substantially as described.

3. In an apparatus or machine of the class described, a horizontal cam shaft driven from a driving shaft, a cam on the first-mentioned shaft connected to one end of and operating a rocking lever, a bar engaged by the opposite end of the said lever, bell-crank levers pivotally mounted on the machine frame and having their inner and lower ends engaging said bar and their upper ends adapted to impart motion to reciprocatingly mounted push rods, substantially as described.

25 4. In an apparatus or machine of the class described, a horizontal cam shaft driven from a driving shaft, a cam on the first-mentioned shaft connected to one end of and operating a rocking lever, a bar raised and lowered by said lever, one or more rods adjustably fitted to said bar and having leaf cams on their upper ends reciprocatingly mounted in and adapted to operate ejector rods recessed in bottom hinge-forming dies, 30 one of said rods having a pivotal connection with the short arm of a bell-crank, the upper end of which is fitted oscillatorily in the front of the last bottom hinge-forming die, substantially as described.

40 5. In an apparatus or machine of the class described, the combination of a plurality of pivotally mounted bell-crank levers, reciprocatingly mounted push rods fitted with pressure pads operated by said levers, and 45 silent buffers on said push rods for the bearing faces of the levers, substantially as described and for the purposes set forth.

6. In an apparatus or machine of the class described, top and bottom hinge-forming dies, ejector rods reciprocatingly mounted in said bottom dies and operated by leaf cams reciprocatingly mounted in said dies at right angles to said rods, substantially as described.

7. In an apparatus or machine of the class described, a die having hinge-forming members formed on the face thereof, a depressible member fitted in the face of said die, a spring or springs for exerting a constant upward pressure and an inclined face on said member, substantially as described.

8. An apparatus for automatically hinging lids to receptacles, comprising a reciprocable ram; dies connected to and movable with the ram; complementary die members mounted in a fixed position in line of movement of the first dies; intermittently operated conveyers for the lids and receptacles located in the front and rear of said fixed dies; and means to push the lids and receptacles from the conveyers onto the fixed dies and to return them to the conveyers, substantially as and for the purpose specified.

9. In an apparatus for automatically hinging lids to receptacles, the combination of a series of sets of hinge-forming dies, one die member of each set being fixed and the complementary die member mounted to have reciprocatory movement toward and away from the fixed die member; conveyers to carry the lids and receptacles and intermittently present them to the successive sets of dies; and means to deliver the lids and receptacles from the conveyers onto the fixed die members and return them to the conveyers, substantially as and for the purpose specified.

In witness whereof I have signed this specification in the presence of two witnesses.

R. C. McCONACHY.
